(57) **CLAIM**

The ornamental design for an exhibition structure, as shown and described.

DESCRIPTION

FIG. 1 is a perspective view of the exhibition structure showing my design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is another perspective view thereof showing exemplary use thereof.

Portions of the exhibition structure shown in broken lines form no part of the claimed design. FIG. 8 shows the exhibition structure with banners attached thereto using fasteners. Portions, including the banners and the fasteners, shown in broken lines are for illustration only and form no part of the claimed design.

The Exhibition Structure is shown with symbolic breaks in its length. The appearance of any portion of the article between the break lines forms no part of the claimed design.
